UNITED STATES PATENT OFFICE.

JOHN W. SPARKS. OF SABINA, OHIO.

BURIAL-VAULT.

No. 892,458.

Specification of Letters Patent.

Patented July 7, 1908.

Application filed June 26, 1907. Serial No. 380,923.

To all whom it may concern:

Be it known that I, JOHN W. SPARKS, citizen of the United States, residing at Sabina, in the county of Clinton and State of Ohio, have invented certain new and useful Improvements in Burial-Vaults; and I do hereby declare the following to be a full, clear, and exact description of the invention, such as will enable others skilled in the art to which it appertains to make and use the same.

The main object of my invention is to provide a practicable and efficient burial-vault, the same being substantially weather-tight, damp-proof and secure against burglary. To this end, my invention comprises an improved vault structure, and improved means for closing, locking and sealing the individual cells of the vault.

A further object of my invention is to provide cell-doors or closures for the individual cells adapted to be temporarily locked, and adapted when desired to become permanently fixed in place, so that thereafter the cells cannot be reopened except by demolishing the structure.

The accompanying drawings which are to be taken as a part of this specification, illustrate an appropriate embodiment of my invention, which will hereinafter be first fully described by reference to said drawings, and then more particularly pointed out in the appended claims.

The invention is susceptible of other embodiments than herein illustrated, and of various modifications as to details of construction and arrangement, so that I do not desire to be limited to the specific construction shown and described.

Figure 1 of said drawings is a perspective view of an appropriate design of burial-vault embodying my invention, which however may be constructed according to numerous designs. Fig. 2 is a horizontal section thereof taken through a tier of individual cells. Fig. 3 is a front view of a vault made in sections anchored together. Fig. 4 is a detail view of one of the anchoring devices. Fig. 5 is an enlarged horizontal section through the outer portion of one cell, showing the lock-plate and front inscription-tablet therein. Fig. 6 shows the back face of the lock-plate or door, with the mechanism carried thereby, which is secured in the mouth or open end of the cell. The lock-bolts carried by the plate are shown retracted, and their

outward or projected portions are indicated by dotted lines. Fig. 7 is a view similar to Fig. 6, illustrating a modification of the lock-plate. Fig. 8 is a front view of the lock-plate. Fig. 9 is a horizontal sectional view of a modified construction of vault in sections. Fig. 10 is a perspective view of the lock-plate and inscription tablet, showing the lock-plate provided with fastening bolts for holding the inscription tablet in place. Fig. 11 is a front view of the inscription tablet with the surrounding portion of the vault structure in section. Fig. 12 is a vertical section through the locking-plate and inscription tablet shown in Fig. 10, said section being taken through one pair of fastening-bolts.

In Figs. 1 and 2 of the drawings, the letter A denotes a vault constructed according to my invention, made as an integral structure of solid concrete, cement or other similar material, as distinguished from a construction of separate blocks, and internally formed with a series or plurality of horizontally arranged individual cells C. These cells are open only at one end, and are respectively adapted to receive individual coffins or burial-caskets, though, if desired, a single cell may be made large enough to accommodate a plurality of caskets.

The integral concrete structure of the vault is strong and durable, practically indestructible by cyclones or similar disturbances of the elements, and not liable to deteriorate and fall apart with age, as in the case of vaults built of separate blocks; besides which the walls of the vault are substantially moisture-proof and weather-tight. To increase these latter characteristics and exclude dampness, sweat and frost from the cells, as well as to jacket the cells against influences of varying outside temperatures, the outer walls of the vault (namely, the back-wall behind the closed ends of the cells and the side walls at opposite sides of the series of cells) are made hollow, or practically double-walled, the dead-air spaces therein being designated by the letter B. As a further protection from moisture, the vault is preferably erected above the surface of the ground, though my invention is not essentially restricted to a structure erected above the ground.

The general plan or design of the vault may be of any appropriate character, as likewise its exterior finish and embellishment. So

also the cells C may be of any convenient or desirable arrangement, though a preferred disposition of the cells is in regular tiers or rows, one above another, as shown. The outer or open ends of the cells are closed by individual inscription tablets D of marble or such other material as desired. Large tablets E for inscription of family names and general data may be made or provided in or on the sides of the vault.

While I have described the vault as an integral structure, I do not intend thereby to exclude its construction in sections, since it may be desirable to add to or increase the size of the vault after its erection. For example, Fig. 3 represents a construction in sections, the original vault structure being indicated by the symbol A¹, and an added section by A². When thus constructed, the sections are or may be secured together by anchors F placed in holes or recesses provided therefor in the adjacent sides of the sections, the holes being filled with cement, mortar or other plastic substance which upon solidifying leaves the anchors firmly embedded in the walls of the sections. The seams or joints between the sections are filled with cement, mortar or the like, or covered with a molding of cement or like substance. If desired, a thin coating of cement may also be applied between the sections, so as to unite them more perfectly and obviate any interior line of separation.

An addition to the vault may be on the sides, or top, or both. Where such an addition is contemplated, the original structure is or may be formed by means of cores or otherwise with the necessary holes for the anchors F, said holes, especially those at the top, being temporarily closed by metallic, wooden or other suitable caps cemented in and over. The recesses in an added section are of course arranged to mate or register with those in the original structure, and all recesses are located where they will not interfere with the cell formations. The anchors F may consist of short pieces of ordinary gas pipe, the ends thereof being split, or spread outward, or mushroomed, as represented in Fig. 4, or other suitable devices may be used adapted to afford an anchorage in the plastic material.

As shown in Fig. 9, another mode of constructing the vault in sections would be by arranging two sections, 1 and 2, back to back and far enough apart to allow additional sections 3 and 4 to be constructed between them, the latter also being arranged back to back, making, when complete, a cross-like structure. Anchorage in this construction may be used, though it is scarcely necessary. This plan would allow the building of one section at a time in the order of the numbers designating the said sections in Fig. 9, which might for some reasons be very desirable.

My invention also contemplates the manufacture of the vaults in sections, for the purpose of facilitating transportation, and the joining of the sections in the manner above described, when the vault is erected at the desired place of installation, each section of the vault, however, being an integral structure of concrete or cement formed with one or more individual cells.

I will now describe my improved means for closing, locking and hermetically sealing the cells, whereby each cell is rendered airtight and substantially burglar-proof, while the closure for each cell is also conveniently adapted either as a temporary or permanent closure. This feature of my invention is not restricted to the integral concrete structure hereinbefore described, but is adapted for general application to other constructions of burial-vaults, as for example a vault of steel or metal. A description of the closure for one cell will suffice, since all the cells are equipped in like manner.

G denotes a metal door or plate, preferably of thick steel, adapted to fit within the mouth or open end of the cell, and having a flange g projecting from its back or inner face. Said plate G being equipped with locking mechanism, may be appropriately termed a "lock-plate". At the back of said plate is a pivotal or rotary disk H, or equivalent element, rigidly-mounted on the inner end of an arbor I, which is journaled in and extends through a central opening in the plate. At the front of the lock-plate, rigidly-mounted on the outer end of said arbor, is a crank J, preferably a double crank-bar equipped with short knobs or handles j, at opposite sides of the arbor, affording a grip for turning the crank and thereby turning the disk H. The front of the plate G is desirably made with a depression or counter-sink for the crank-bar, although this is not essential.

At preferably diametrically opposite points on the disk H, are pivotally-attached the inner ends of oppositely-projecting lock-bolts K, which are guided through or under loops k on the back of the plate. By turning the disk H in reverse directions, by means of the crank-bar J, said lock-bolts K can be moved outward and inward, so as to engage in or with and disengage from suitable sockets or catches in the walls of the cells; the turning of the crank J in one direction throwing out the lock-bolts beyond the perimeter of the plate, and the reverse movement of the crank retracting said lock-bolts within the perimeter of the plate. The disk H may have a raised hub h¹ which will back up the inner ends of the lock-bolts when shoved outward to locking position. Instead of two diametrically-located lock-bolts, it would be practicable to employ three or more lock-bolts arranged at different positions on the back of the lock-plate, and adapted to engage in cor-

respondingly-arranged sockets or catches therefor in the cell-walls, though the arrangement shown is preferred.

As shown in Figs. 5 and 6, adjustable set-screws k^1 are tapped through the loops k and swiveled to small plates or washers k^2 , the latter bearing on the lock-bolts K , so as to hold them toward the plate. Or, as shown in Fig. 7, similar set-screws may pass through longitudinal slots in the lock-bolts and be tapped in the lock-plate itself, suitable washers k^3 being interposed between the lock-bolts and the heads of the set-screws. This adjusting feature, while constituting a subsidiary feature of my invention, is not indispensable.

The disk H , which may appropriately be termed a "ratchet-disk", has a segment of its periphery made or provided with ratchet-teeth h , engaged or adapted to be engaged by a spring-pressed pawl L , which is pivotally-mounted on the plate G and normally held in engagement with the teeth of the ratchet-disk H by its spring l . The arrangement of the ratchet-teeth h and pawl L is such as to permit turning the ratchet-disk only in a direction to project or force outward the lock-bolts K , but prevent the withdrawing or retracting of the lock-bolts. However, the pawl can be disengaged and held disengaged from the ratchet-disk, so as to permit turning the latter in either direction; the purpose of which will appear later. Various contrivances may be adopted for this purpose; two suitable arrangements being represented in Figs. 6 and 7 respectively. In Fig. 6, the spring l is shown bearing the pawl L against the ratchet-disk. To set the pawl out of engagement, it is merely necessary to place the spring under the pawl, or between the pawl and ratchet-disk, as indicated by dotted lines; the spring thus doing double duty. In Fig. 7, the spring l is shown as a tail-lever of the pawl L , acting between the pivot of the pawl and a stud l^1 . To disengage the pawl from the ratchet-disk, the spring may be placed under another stud l^2 closer to the ratchet-disk.

Between the disk H and plate G , surrounding the arbor I , is a gasket or packing M of rubber, asbestos, or other suitable compressible packing material, placed in opposed concavities in the confronting faces of the disk and plate. The compressing of this packing, effected by drawing the disk H against the plate G , crowds it around the arbor I and thereby makes an air-tight joint, so as to prevent access of air or moisture through the central opening of the plate. For drawing the disk against the plate, oppositely arranged segmental inclines or raised inclined surfaces N are provided on the front of the plate, under the respective arms of the crank-bar J , the highest portions of the inclines being under that position which the crank-bar occupies when the lock-bolts are thrown outward.

Hence, by turning the crank-bar in a direction to force out the bolts, said crank-bar will ride on the inclined surfaces and thereby draw the disk H against the plate G compressing the aforesaid packing M . One end of the crank-bar J is provided with an apertured lug or flange j^1 . The front of the plate G is provided with a segmental flange g^1 , having preferably a plurality of apertures therein, and located so as to confront the flange j^1 when the crank-bar J is moved to locking position, by which is meant the position for forcing out the lock-bolts K . The hasp of a pad-lock may then be entered through registering apertures in the flanges j^1 and g^1 , in order to lock the crank-bar in said locked position, for a purpose hereinafter explained.

The above described lock-plate G sets or fits within the mouth or open end of the cell, and against a shoulder or abutment c therein, the back flange g of the plate also fitting within the shoulder c . Said shoulder is desirably provided by abruptly enlarging the mouth of the cell, or forming a rabbet around the mouth of the cell. Behind said shoulder c are the recesses or sockets c^1 in the cell-walls for reception of the outer ends of the lock-bolts K . The front walls of said sockets c^1 are faced with metal embedded in the plastic structure, the metal fastenings or catches preferably consisting of substantially **Z**-shaped anchors O embedded in the structure in the manner represented in Fig. 5. The opposing surfaces of the shoulder c and plate G are formed with continuous mating or confronting grooves indicated by c^2 and g^2 respectively, designed to receive a packing or sealing substance P , as cement, asbestos, rubber or other suitable material; so that when the plate G is shoved back against the shoulder c , the said packing or sealing substance will establish an air-tight connection, which, in addition to the air-tight seal around the arbor I of the plate G , makes the whole structure hermetically sealed. To draw the lock-plate against the shoulder c , the outer ends of the lock-bolts K are desirably offset or inclined backwardly from the plate G , so that as said lock-bolts are forced outward and into the recesses c^1 , they will ride against the metallic anchors or catches O , and thereby forcibly draw the plate G inward, compressing the packing or seal P between the plate and shoulder c .

Prior to depositing a body in one of the cells, the lock-plate G thereof is detachable, the spring-pawl L being disengaged from the ratchet-disk H so as to permit the lock-bolts K to be withdrawn from the recesses or catches in the cell-walls by a reverse turning of the crank-bar J . After depositing a body or casket in the cell, the lock-plate is put in position, and may be either temporarily or permanently secured, according to circumstances. If only a temporary closure is de-

sired, the pawl L is still held disengaged from the ratchet-disk H, so as to permit turning the crank J in either direction, for moving the lock-bolts into or out of engagement with the sockets or catches in the cell-walls. When the mechanism of the lock-plate is so adjusted for temporary locking, the crank-bar J may be locked in position by means of a pad-lock, the hasp of which may be inserted through apertures in the flanges j^1 and g^1 as before mentioned, so as to insure against any unauthorized or promiscuous access to the cell. But when it is desired to make a permanent closure, the pawl L is released and allowed to engage the ratchet-disk H, and the lock-plate G is then shoved back into position against its stop or shoulder c, a supply of cement, mortar or the like, or a packing of other suitable substance, being first interposed in the grooves c^2 , g^2 between the lock-plate and shoulder c. The crank-bar J is then turned to force the lock-bolts K outward and into the recesses or sockets in the cell-walls; and, as said lock-bolts move outward, their inclined ends ride against the metallic anchors O, thereby drawing the lock-plate G inward against the shoulder c, and compressing the interposed cement or packing P, while the turning of the crank-bar J on the inclines N also effects compression of the packing M around the arbor I, as before explained, thus hermetically sealing the tomb. It is now impossible to withdraw the lock-bolts K by any means whatsoever, and access to the cell cannot be had except by demolishing the structure, which, by reason of its strong concrete formation, is practically secure against depredation.

It may also be desirable to erect a wall of cement in the space between the end of the coffin and the steel plate or door G. For this purpose, a wooden board or other suitable plate should be fitted in the cell against the end of the coffin, and the space between said board or plate and the shoulder c should be filled with soft cement. The lock-plate G would then be pushed back against this soft cement wall, and secured in position by turning the crank-bar J, so as to project the lock-bolts K into the sockets therefor in the cell-walls. Later the cement will harden or set on the mechanism of the lock-plate, thus increasing the security and tightness of the seal, although this is not essential since the lock-plate and mechanism described are perfectly effective.

The inscription tablet D is inserted in the mouth of the cell after the lock-plate G is secured in position, and it may rest against the front of the lock-plate, or, if preferred, there may be an intervening space between the lock-plate and the tablet D which can be filled with cement when the cell is permanently sealed. The tablet D is desirably formed with a groove d around its perimeter,

and the mouth of the cell is formed with a mating groove a. In sealing the cell, said grooves are filled with cement and the tablet D is pushed in place, whereupon the cement in the two grooves will meet and set, forming a secure fastening for the tablet, also making an additional sealing for the cell. It is necessary, of course, to hold the tablet in position until the cement hardens. This may be done by any suitable means. For example, in order to hold the tablet temporarily in place, dowel-pins d^1 may be provided in either the upper or lower edge of the tablet preferably the upper edge, as shown in Figs. 10 and 11, these pins adapted to enter recesses therefor in the corresponding wall of the mouth of the cell. In putting the tablet in place, the tablet would first be held in position to engage the dowel-pins in the recesses therefor, and then the tablet would be lifted, and at the same time shoved back into position.

Another means of holding the tablet in place, is shown in Figs. 10 and 12, where bolts or threaded rods are entered through loops or hooks r on the face of the lock-plate G; said bolts or rods adapted to pass through holes therefor in the tablet and to receive finished washers and nuts r^1 to hold the tablet in place. The nuts r^1 may be made of ornamental designs. This arrangement is especially desirable for the temporary closure. It may also be used for the permanent sealing of the cell, either alone, or in combination with the means already described, the bolts holding the tablets securely while the cement in the mating grooves a and d hardens.

I do not, of course, desire to be limited to any specific means for holding the tablet in place, the means shown herein being illustrated only by way of example.

In the following claims, I intend the term "concrete", as applied to the structure of the vault, to be construed as including concrete proper, or cement or admixtures therewith, and other similar plastics commonly embraced under the generic name "concrete" such substances being mixed with such ingredients as broken stone, gravel, etc., if desired.

I make no claim to the lock-plate and its mechanism *per se* since the same constitutes the subject-matter of my divisional application filed September 6, 1907, Serial No. 391,638.

Having thus fully described my invention, what I claim as new and desire to secure by Letters Patent of the United States is:

1. A burial-vault comprising a concrete structure having therein an open-ended cell to receive a burial-casket, the mouth of the cell being rabbeted, thereby providing an internal shoulder, a plate fitted within the mouth of the cell against said shoulder, said shoulder and plate having mating grooves

115

filled with sealing material, locking mechanism carried by said plate, means for actuating the same from the outside of said plate, metallic devices secured in the cell for engagement by said locking mechanism, and a tablet fitted within and closing the front of the cell, said tablet and the cell-walls having mating grooves filled with sealing material.

2. A burial-vault comprising a concrete structure having an open-ended cell therein, a plate fitted in the mouth of the cell, locking mechanism carried thereby comprising lock-bolts adapted to move outward, the cell-walls having sockets to receive said lock-bolts, and substantially Z-shaped metallic catches embedded in the walls of the cell and having their front end-portions disposed to provide metallic facings for the front walls of said sockets, for engagement by said lock-bolts.

3. A burial-vault comprising a concrete structure containing a cell having an entrance mouth, a closure plate designed for

arrangement in said mouth, a means for securing the closure plate in place, an inscription tablet adapted to seat in the mouth of the cell outside of the closure plate and means for connecting the plate and tablet one with the other.

4. A burial-vault, comprising a concrete structure containing a cell having an entrance mouth, a closure plate fitted in said mouth, a means for permanently securing said plate in place to wholly prevent its subsequent removal, an inscription tablet designed to fit within said mouth at the outer side of the closure plate, a means for connecting the tablet to the closure plate and sealing means for fixedly securing the tablet in place.

In testimony whereof I affix my signature, in presence of two witnesses.

JOHN W. SPARKS.

Witnesses:

C. R. ELLIS,
F. E. BOTTFENFIELD.
